UNITED STATES PATENT OFFICE.

ISAIAH RICHARDS, OF AU SABLE FORKS, NEW YORK.

BANDED BARKER.

1,005,654.

Specification of Letters Patent. Patented Oct. 10, 1911.

Application filed June 25, 1910. Serial No. 568,834.

To all whom it may concern:

Be it known that I, ISAIAH RICHARDS, a citizen of the United States, and a resident of Au Sable Forks, in the county of Essex 5 and State of New York, have invented a new and Improved Banded Barker, of which the following is a full, clear, and exact description.

This invention relates to a new and improved barker for removing the bark from logs which are to be made up into paper pulp, and particularly relates to reinforcing means, in the nature of bands, for strengthening and lengthening the life of the barker.

An object of this invention is to provide a device which will be simple in construction, inexpensive to manufacture, exceedingly strong and durable, and efficient in its operation.

A further object of this invention is to provide a barker comprising a plurality of members, spaced apart one from the other and secured to heads with bands encircling the same throughout the majority of the 25 circumference, whereby the strength, rigidity and durability of the structure as a whole is materially increased.

These and further objects, together with the construction and combination of parts, 30 will be more fully described hereinafter and particularly set forth in the claims.

Reference is to be had to the accompanying drawings forming a part of this specification, in which similar characters of reference indicate corresponding parts in all the views, and in which—

Figure 1 is a sectional view through a tank, showing the barker in position; Fig. 2 is a vertical transverse section through the 40 barker; Fig. 3 is an enlarged detail perspective view, showing the adjustable ends of one of the bands and the means for adjusting the same; Fig. 4 is a fragmentary transverse section taken at the middle of the barker, and showing the method of securing the middle band at the point where the door is located; and Fig. 5 is an enlarged detail 45 section through one end of one of the bands, showing its connection with the tightening 50 devices.

Referring more particularly to the separate parts of the device, 1 indicates a suitable foundation, which also forms a pit 2, in which extends a barker 3, which is rotatably 55 supported in any well known manner on the base 1, as by means of a shaft 4. The shaft

4 is secured in center castings 5, which are extended by means of plates 6 to form enlarged circular heads, to which are secured in any well known manner a plurality of members 7. These members may be in the form of T-bars, angle-irons, or, as shown, in the form of channel bars, and are disposed in spaced relation, so as to permit the fluid, such as water, with which the bark on the log being stripped is moistened, to pass through. The structure thus described, while efficient, may not be of sufficient durability to fill all purposes to satisfaction. There are therefore provided one or more 70 bands 8, 9 and 10, which encircle the members 7 for a portion of the circumference of the barker, and are adapted to form reinforcing tie members for strengthening the structure. While any number of these bands 75 may be used, it is preferable to provide three; one at each end and one in the center.

In order that access may be had to the interior of the barker, for the purpose of inserting and removing the logs treated, there 80 is provided a door 11, which is openable in any well known manner. At the point where the door is located, the side bands 8 and 10 pass into the interior of the barker, as will be noted at the section 12 in Fig. 2, 85 so as to permit the door to be opened without destroying the continuity of the encircling bands. In case of the intermediate or central band 9, it is undesirable to have the band stretch across the door opening, 90 for the reason that it would not be so easy to insert and withdraw the logs. It is therefore desirable to terminate the band 9 at points 13 and 14 and secure the ends thus formed to bars 15 and 16, which are preferably made of steel and inserted between the flanges of the members 7. Besides the bars 15 and 16, the members 7 next adjacent thereto are also provided with iron bars 17, which take up the strain at the ends of the 100 center band 9 adjacent the door 11. The remainder of the members 7, with the exception of those composing the door 11, are provided with wooden bars 18, which are inserted beneath the bands 8, 9 and 10, in a 105 dry condition, so that when they are moistened by the solution which moistens the bar on the logs treated, they will swell and thereby tighten the band, and wedge themselves between the bands and the members 7, forming an exceedingly strong structure. This in itself might be sufficient to

- form all the necessary tightness for the bands 8, 9 and 10, but is desirable, for the purpose of adjusting, that these bands be provided with further means of tightening.
- 5 For this purpose, each of the bands, 8, 9 and 10 is provided with loop ends 19 and 20, which may be formed in any suitable manner, as by riveting folded strips to each side of the ends of the band.
- 10 Located in the loops 19 and 20, there are provided pins 21 and 22, each of which is provided at each end with openings, through which extend bolts 23 and 24. These bolts are threaded at one or both of their ends 15 to form adjustable engaging portions with nuts 25 and 26, whereby the distance between the pins 21 and 22, and thus between the ends of the bands, may be adjusted within certain limits.
- 20 It will thus be seen that there is provided a device of exceedingly great strength and durability, which will perform the work desired in an efficient and thorough manner.
- While I have shown one embodiment of 25 my invention, I do not wish to be limited to the specific details thereof, but desire to be protected in various changes, modifications and alterations which may come within the scope of the appended claims.
- 30 Having thus described my invention, I claim as new and desire to secure by Letters Patent:—
1. The combination with a pair of heads spaced apart, of a plurality of members secured to said heads in spaced relation, and one or more bands encircling said members for a portion of their length and extending inside of some of said members for the remainder of their length.
- 35 2. The combination with a pair of heads, of a plurality of members secured to said heads in spaced relation so as to form seepage passages therebetween, some of said members comprising an openable door permitting access to the interior chamber surrounded by said members, and one or more bands 40 embracing some of said members and extending into the interior of said chamber at the point where said door is located.
- 45 3. The combination with a pair of heads, of a plurality of members secured to said heads in spaced relation so as to form seepage passages therebetween, some of said members comprising an openable door permitting access to the interior chamber surrounded by said members, one or more bands 50 embracing some of said members and extending into the interior of said chamber at the point where said door is located, and another of said bands terminating on either side of said door.
- 55 4. The combination with a pair of heads, of a plurality of members secured to said heads in spaced relation so as to form seepage passages therebetween, some of said members comprising an openable door permitting access to the interior chamber surrounded by said members, one or more bands 60 embracing some of said members and extending into the interior of said chamber at the point where said door is located, and means for tightening said bands.
4. The combination with a pair of heads, of a plurality of members secured to said heads in spaced relation so as to form seepage passages therebetween, some of said members comprising an openable door permitting access to the interior chamber surrounded by said members, one or more bands 65 embracing some of said members and extending into the interior of said chamber at the point where said door is located, and means for tightening said bands.
5. The combination with heads, of a plurality of members secured to said heads in spaced relation, a plurality of bands embracing said members, some of said members forming a door and one of said bands terminating on either side of said door, and reinforcing metallic bars secured to the ends of said last-mentioned band and adapted to 70 resist the strain incident to the fastening of said ends to said members.
6. The combination with heads, of a plurality of members secured to said heads in spaced relation, a plurality of bands embracing said members, some of said members forming a door and one of said bands terminating on either side of said door, reinforcing metallic bars secured to the ends of said last-mentioned band and adapted to 75 resist the strain incident to the fastening of said ends to said members, and means for tightening said bands.
7. The combination with a body portion comprising a pair of heads and a plurality of members secured to said heads in spaced relation, of a plurality of bands embracing said members, some of said members comprising a door for permitting access to the interior of said body portion, some of said 80 bands extending into the interior of said body portion at the point where said door is located, and another of said bands terminating on either side of said door.
- In testimony whereof I have signed my 85 name to this specification in the presence of two subscribing witnesses.
- ISAIAH RICHARDS.
